(57) **CLAIM**

The ornamental design for a medicament access device, as shown and described.

DESCRIPTION

FIG. 1 is a front, right perspective view of a medicament access device showing our new design in a first configuration;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a front, right perspective view of the medicament access device in a second configuration.

The long-dash short-dash broken lines in the figures show boundaries of the claimed design and form no part of the claimed design. The pairs of adjacent bracketed wavy break lines shown in FIGS. 1-5 form no part of the claimed design and indicate that the appearance of any portion of the article between the break lines forms no part of the claimed design. All other broken lines show portions of the medicament access device that form no part of the claimed design.
